UNITED STATES PATENT OFFICE

JAMES H. O'NEIL, OF SYRACUSE, NEW YORK, ASSIGNOR TO CONTINENTAL CAN COMPANY, INC., OF NEW YORK, N. Y., A CORPORATION OF NEW YORK

APPARATUS FOR CLOSING VACUUMIZED CONTAINERS

Application filed February 27, 1929. Serial No. 343,131.

The invention relates to new and useful improvements in an apparatus for closing vacuumized containers.

An object of the invention is to provide an apparatus wherein a container may be vacuumized after it is filled and closed, and wherein said container may be sealed by a closure forced into gripping contact with a friction seat by pressure applied thereto.

10 A further object of the invention is to provide an apparatus of the above character wherein the friction seat to receive the closure is located centrally of the closing end for the container, and wherein the end surface 15 rounding the friction seat is supported magnetically from without so that it may be firmly held, resisting the pressure applied to the closure for seating the same.

A still further object of the invention is 20 to provide an apparatus of the above character for seating annular closures, and wherein magnetic means is provided for supporting the end within the friction seat to resist the pressure incident to the seating of 25 the closure.

These and other objects will in part be obvious and will in part be hereinafter more fully disclosed.

In the drawings which show by way of 30 illustration, a part of an apparatus embodying the improvements—

Figure 1 is a vertical sectional view through a vacuumizing bell and also through the container which is being vacuumized and closed, and showing the closing head in side elevation;

Fig. 2 is an enlarged vertical sectional view through the closing head and the upper portion of the container, said section being taken on the line 2—2 of Fig. 3;

Fig. 3 is a sectional view on the line 3—3 of Fig. 2, and

Fig. 4 is a detail showing the closure seated and the container sealed; in this figure, the end is provided with a recess to receive and house the closure.

The invention is directed to the sealing of a container which has been vacuumized after the container has been filled and closed. The 50 container is filled, after which the closing

end is attached thereto, preferably by double seaming. This closing end is formed within its limits, and preferably centrally thereof, with an annular recess. In the bottom of the recess there are openings leading to the container. The container is closed, so far as further filling is concerned, but is still open to the extent that a vacuum can be drawn on the container. The container is then closed by a closure or plug which is shaped so as to engage the side walls of the recess and frictionally grip the same. Either the closure or the container end is provided with a sealing material. The sole means, however, for holding the closure in place, is the frictional gripping contact between the walls of the closure and the walls of the recess into which the closure is forced. The invention is directed primarily to an apparatus for placing a container under vacuum, and for forcing the closure into the recess for sealing the container. The container, after it is filled and closed by the attachment of the end thereto, is placed in a chamber, and a vacuum drawn on the chamber places the interior of the container under vacuum. Within this chamber is the closing head which includes magnetic means for engagement with the outer face of the end of the container in the regions surrounding this recess, and also in the region within the recess, when it is annular. The head is also provided with a plunger which engages the closure for forcing the same into the recess. This magnetic support of the end resists the pressure incident to the forcing of the closure on to its friction seat, and thus enables the closure to be firmly seated without any strain being placed on the container end.

Referring more in detail to the drawings, the invention is shown as applied to the closing of a container which includes a body portion 1, to which an end 2 is joined by a double seam 3. This end 2 is provided with an annular recess 4. The side walls 5 and 6 of the recess are substantially vertical. At the bottom of the recess there is a series of openings 7. The container is filled in the usual manner, after which the end 2 is dou-

ble seamed thereto. This container is placed in a vacuum chamber. Purely for the purpose of illustration, I have shown a support 8 on which the container is placed, and a vacuum bell 9 which is adapted to surround the container. Said bell is provided with a gasket 10 which engages the support forming an airtight connection therewith. A pipe 11 is secured to the bell and to a suitable apparatus for drawing a vacuum on the bell. It will be understood that either the support may be moved relative to the bell, or the bell relative to the support, for the enclosing of the container in the chamber formed by the bell. It will also be understood that any other suitable means may be provided for enclosing the container to form thereabout a chamber which may be placed under vacuum.

Located within this bell 9 is the closing head. The closing head includes a supporting shaft 12 which is connected to suitable means so that it may be moved vertically to a limited extent within the bell. At the lower end of the shaft is a head 13 which is preferably formed integral therewith. Spaced from this head 13 is an annular plate 14. This annular plate 14 is secured to the head 13 by supporting rods 15, which may be of any suitable character. As shown in the drawings, there are four rods. At the immediate lower face of the head 13 there is an annular plate 16. Surrounding each rod 15 is a sleeve 17. This sleeve lies between the plates 14 and 16, and the sleeves form spacers so that the annular plates are firmly secured to the head 13. Located between these annular plates 14 and 16 is a series of coils, each of which has a core 18 on which the coils 19 are wound. This core is shown as provided with projecting portions 20, 21 which engage similarly shaped recesses, respectively, in the annular plates 14 and 16. This serves as a ready means for firmly supporting the coils. Centrally of the magnetic head, there is a coil 22 which includes a central core 23 which is threaded into the head 13. These coils, when energized, produce an annular magnet of the plate 14 and also a magnet of the head 23^a of the core of the central coil. This annular plate 14 is preferably of such dimensions as to freely pass into the depression formed in the container end 2, so as to make contact with the metal of the container end in the region surrounding the recess 4. The central magnetic head 23^a makes contact with the central portion of the container end; that is, the portion disposed within the annular recess 4.

The container as above described is sealed by means of a closure 24. This closure is annular, and as shown, is formed with horizontally extending portions 25, 25 between which is an annular recess 26. The walls 27

and 28 thereof are substantially vertical. The recess 26 is so proportioned that these walls 27 and 28 will make firm gripping frictional contact with the walls 5 and 6, respectively, when the closure is forced into the recess 4. In Fig. 4, the can end 2 is shown as provided with a recess 2^a, and the closure 24 seats in this recess and is housed therein. When the closure is flush with the can end, there is no chance of prying out the closure plug. A coating C is either applied to the closure or the inner face of the recess as indicated in Fig. 4. This enables a vacuum-tight seal to be produced.

Located within the closing head is a plunger 29. This plunger includes 4 segments. The head 13 is formed of cross arms disposed at right angles to each other, and these segments freely move in the angular space between these arms. The plunger is carried by a sleeve 30 which surrounds the shaft 12, and which is independently moved on the shaft by suitable means. The closure 24 may be placed lightly on the container before the container is placed in the vacuum chamber. It may be secured to the closing head. As shown in the drawings, this closure is supported by the plunger 29 and held away from the container. This is not necessary. If it is lightly placed on the container, then when the vacuum chamber is placed under a vacuum, the air and gases in the container will be drawn through the openings 7, and the closure lifted to permit the vacuumizing of the container. The container may, in fact, be placed under vacuum before the closing head is brought into contact with the container. The head is brought into contact with the container so that the magnets make contact with the outer face of the container end. When the head is magnetized, these magnets will firmly support the metal of the container end, and while thus supported, the plunger 29 will force the closure into the recess in the container end. Inasmuch as the metal of the container end is supported all the way around the recess, and also centrally of the recess, the closure may be forced with considerable pressure on to its friction seat and the supported end will resist this pressure. The end being held by the magnets, will not be forced inward by the seating of the closure and no strain will be placed on the double seam joining the end to the container body. Furthermore, when the end is supported magnetically so as to resist a considerable pressure applied to the closure, the closure may be made of such dimensions as to very tightly seal the container when the closure is forced on to the friction seat therefor.

It will be understood that the container seating recess and the closure therefor, may

be greatly changed as to structure. The essential feature, however, which should be retained, is the frictional seating of the closure by a downward thrust or pressure applied to the closure. It will be understood also that the closing head may be greatly modified as to structure, the essential features which should be retained are the magnetic support applied to the outer face of the container end for firmly holding the same, and the pressure means which forces the closure on to its frictional seat while the end is thus supported. The present embodiment of the invention is solely for the purpose of making clear the essential elements of the container and closing head for closing the same.

While the invention is shown as applied to the forcing of a closure into a friction seat on the container end for sealing openings through which the container has been vacuumized, it will be understood that the closing head may be used for other purposes where it is desired to seat a closure on a friction seat formed in a container end, and at the same time, support the container end adjacent the friction seat so as to resist the pressure incident to the forcing of the closure on to its seat.

Having thus described the invention, what I claim as new and desire to secure by Letters Patent, is—

1. An apparatus for sealing containers having a friction seated closure, said apparatus comprising magnetic means for supporting the container wall in the region of the friction seat therein, and means for applying pressure to the closure for seating the same.

2. An apparatus for sealing containers having a friction seated closure, said apparatus comprising means for vacuumizing the container, magnetic means for supporting the container wall in the region of the friction seat therein, and means for applying pressure to the closure for seating the same.

3. An apparatus for sealing containers having an annular recess in the end thereof adapted to receive a friction seated closure, said apparatus comprising means for vacuumizing the container, magnetic means surrounding said recess and engaging the container end for supporting the same, and means for applying pressure to the closure for seating the same in the recess.

4. An apparatus for sealing containers having an annular recess in the end thereof adapted to receive a friction seated closure, said apparatus comprising magnetic means surrounding the recess and engaging the container end for supporting the same, magnetic means engaging the container end within said recess for supporting the same, and means for applying pressure to the

closure for seating the same in said recess.

5. An apparatus for sealing containers having an annular recess in the end thereof adapted to receive a friction seated closure comprising a shaft, a supporting head carried thereby, ring members spaced from each other and carried by said head one above the other, coils disposed between said ring members for magnetizing the same, the lowermost ring member being adapted to engage the container end in the region adjacent the recess for supporting the same, a sleeve carried by said head, and plunger members supported by said sleeve adapted to engage the closure for seating the same in said recess and sealing the container.

6. An apparatus for sealing containers having an annular recess in the end thereof adapted to receive a friction seated closure comprising a shaft, a supporting head carried thereby, ring members spaced from each other and carried by said head one above the other, coils disposed between said ring members for magnetizing the same, the lowermost ring member being adapted to engage the container end in the region adjacent the recess for supporting the same, a sleeve carried by said head, plunger members supported by said sleeve adapted to engage the closure for seating the same in said recess and sealing the container, said head having a central member adapted to engage the container end adjacent the inner side of the recess, and a coil for magnetizing said central member.

7. An apparatus for sealing containers having a friction seated closure, said apparatus comprising a vacuum chamber in which said container may be placed and vacuumized, a closing device located within said chamber and including magnetic means adapted to engage the end of the container having the friction seat for supporting the same, and a plunger adapted to engage the closure for applying pressure thereto for seating the same.

In testimony whereof, I affix my signature.

JAMES H. O'NEIL.
